(57) **CLAIM**

The ornamental design for a musical instrument stand, as shown and described.

DESCRIPTION

FIG. 1 is a top right perspective view of an assembled exemplary musical instrument stand showing my new design;

FIG. 2 is a top plan view, the bottom being plain and unornamented;

FIG. 3 is a front elevational view;

FIG. 4 is a rear elevational view;

FIG. 5 is a left side elevational view, the right side elevational view being a mirror image; and,

FIG. 6 is a view like that of FIG. 1 but with exemplary (only) supports for the body and neck of a string musical instrument shown in dotted line.

The broken line showing of supports for the body and neck in FIG. 6 is for illustrative purposes only and forms no part of the claimed design.
